CLAIM

The ornamental design for a two way radio as shown and described.

DESCRIPTION

FIG. 1 is a perspective view of a two way radio showing my new design;

FIG. 2 is a perspective view of a two way radio showing my new design;

FIG. 3 is a top plan view thereof;

FIG. 4 is a rear elevational view thereof;

FIG. 5 is a bottom plan view thereof;

FIG. 6 is a right side view thereof;

FIG. 7 is a front elevational view thereof; and

FIG. 8 is a left side view thereof;

The broken lines in the drawings depict portions of the TWO WAY RADIO that form no part of the claimed design.
